R. B. ANDERSON, OF ONEIDA, ILLINOIS.

Letters Patent No. 79,180, dated June 23, 1868.

IMPROVEMENT IN SECURING BUCKLES AND RINGS TO HARNESS.

The Schedule referred to in these Letters Patent and making part of the same.

TO ALL WHOM IT MAY CONCERN:

Be it known that I, R. B. ANDERSON, of Oneida, in the county of Knox, and in the State of Illinois, have invented certain new and useful Improvements in Mode of Securing Buckles and Rings to Harness; and do hereby declare that the following is a full, clear, and exact description thereof, reference being had to the accompanying drawings, and to the letters of reference marked thereon.

In the annexed drawings, making part of this specification, A represents any leather strap to which it is desirable to secure a ring or buckle, or snap-hook. B represents a metallic loop or box, which is open at both ends, and which is made tapering or flaring in shape.

In using this loop or box the strap is first cut in a tapering or wedge-shape at its end, and then passed through the ring or buckle, and then doubled down, as seen in the figure. The box B is then slipped over the strap thus doubled, and pressed up snugly toward the ring or buckle, and when so pressed up that it fits tightly over the strap, screws or rivets dd are passed through the box, and through the strap, and hold the parts firmly together. When screws are used, the buckle or ring may be readily removed, by taking out the screws and slipping back the box B.

Having thus fully described my invention, what I claim as new, and desire to secure by Letters Patent, is— Securing buckles or rings to leather straps by means of a tapering metallic box, B, secured by screws dd, whereby the end of strap is enclosed, as specified.

In testimony that I claim the foregoing, I have hereunto set my hand, this 8th day of March, 1868.

R. B. ANDERSON.
